UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR A SPOON, &c.

SPECIFICATION forming part of Design No. 20,842, dated June 16, 1891.

Application filed April 28, 1891. Serial No. 390,842. Term of patent 14 years.

To all whom it may concern:

Be it known that I, GILBERT L. CROWELL, Jr., a citizen of the United States, and a resident of Arlington, in the county of Hudson and State of New Jersey, have invented and produced a new, original, and useful Design for Handles for Spoons, Knives, Forks, and other Like Articles, of which the following is a description, reference being made to the accompanying drawings, which fully illustrate the design as applied to a spoon-handle and are made a part of the following specification.

The general outline of the handle is of a wavy or recurring character, the convexities and concavities on one side being opposite those on the other side, and the outline converges without interruption from the upper widest portion of the handle along the narrow shank portion and to the shoulders of the bowl.

Figure 1 shows the front of the handle. At the top thereof is a shield *a*, the field of which is plain, and which is crowned by the shell *b*, and around the sides of the same is a border of scrolls *c*. Beneath the shield is the Cupid figure *d*, topping and mainly surrounded by

the scroll-work *e*, from which centrally hangs a line of buds extending down the shank. The shank bears the marginal beads *f*, and at the lower end the shank widens and bears the spray scroll-knot *g*.

The bowl may have any desired configuration and form of concavity.

Fig. 2 shows the back of the handle. The shield *h* is plain and is marginally bounded by scrolls, which join at the bottom of the shield the vine and leaf ornamentations. The edges of the shank bear the beads *j*, and at the lower end of the shank is the radiate scroll-piece *k*.

What is claimed as new is—

1. The design for the handles for spoons, knives, forks, and like articles, substantially as herein shown and described.
2. In the design for the handle of a spoon herein described and shown, the front thereof.
3. In the design for the handle of a spoon herein described and shown, the back thereof.

GILBERT L. CROWELL, JR.
